COLLATING MACHINE

Wilbur D. Warner, Chicago, Ill.

Application February 3, 1940, Serial No. 317,087

7 Claims. (Cl. 270—58)

This invention relates to an apparatus for collating sheets of paper.

Heretofore, sheets of paper have been collated entirely by hand or by the aid of complicated and rather costly apparatus. One such prior art apparatus comprises an electrically driven turntable, on which the stacks of sheets to be collated are positioned. In the operation of this device, an operator stands at a fixed station adjacent to the turntable and picks off and collates the top sheet from each stack as the stacks are carried before him by the rotating turntable.

Aside from the matter of initial cost, these prior art collating devices are objectionable because of their size and the consequent requirement for a large operating space and because they cannot be operated economically. A further objection resides in the fact that they tend to break down, thereby necessitating costly repairs and delays.

The collating machine in accordance with the present invention is a simple, inexpensive and compact apparatus which is free from the objections attendant to the prior art apparatus. There is very little likelihood of breakdown, but should such breakdown occur, repairs can be made quickly and inexpensively, thus avoiding undue and costly delays. The present invention has many other advantages which will be apparent from the following description.

The collating machine in accordance with the present invention comprises, in general, a plurality of trays or shelves designed to support a plurality of individual stacks of sheets to be collated and a simple, mechanically operable mechanism designed to eject individual sheets from the tops of the individual stacks and feed them forwardly to the desired collating position so that they may be thus readily grasped by the operator.

The present invention will be fully understood from the following detailed description of a preferred embodiment of my invention. It is, of course, to be understood that my invention is not to be limited to the details of the specific mechanism shown and herein described since this mechanism may be varied rather widely, as desired, without departing from the principle of operation and from the scope of the appended claims.

Referring to the drawings:

Figure 1 is a vertical elevational view of my collating machine, with parts broken away, substantially along the lines 1—1 of Fig. 3 and showing the sheet ejecting mechanism in the initial

operative position, the midsection of my machine being eliminated;

Fig. 2 is a fragmentary view, similar to Fig. 1, but showing the position of the mechanism after the individual sheets have been ejected from the individual stacks; and

Fig. 3 is a transverse sectional view through my apparatus taken substantially along the lines 3—3 of Fig. 1.

In the drawings there is shown a framework, 10 suitably of wood, metal or the like, comprising a base 10, a side wall 12 extending substantially the length of the base, back wall 14 and a short side wall 16 extending a short distance forwardly from the back. The front and a large 15 portion of one side of the framework are open to permit free access to the interior for the purpose of placing and arranging the stacks of paper sheets 15 to be collated in the desired position.

A partition 18 is provided between walls 12, 16 20 to house the operating mechanism and to serve as a back stop for the stacks of sheets. Preferably, the partition is inclined and as shown in the drawings the inclination extends toward the rear wall as the top of the machine is approached. The partition or back stop 18 is slotted substantially throughout its length, as at 20.

A plurality of trays or shelves 22 are secured to wall 12 and partition 18 one above the other. Each shelf is designed to support a single stack 30 of sheets. As shown, shelves 22 are inclined upwardly towards the front of the machine and may form an angle of less than 90° with back stop 18. By virtue of this construction, a stack of sheets when positioned on a platform, as shown, will be 35 cracked or rifled, thereby removing the normal tendency of some of the sheets to adhere one to the other. This tendency is particularly manifest if the edges of the stack of sheets have been cut or sheared. This cracking of a stack of sheets 40 may also be effected if the shelves form with the back stop an angle of greater than 90° and such construction may be used, if desired. Obviously, of course, shelves 22 may be normal to back stop 18, but in such construction cracking of the 45 stack of sheets cannot be so readily effected.

The mechanism for simultaneously ejecting the individual top sheets from each of the stacks 15 comprises a shaft 25 which extends between walls 12 and 16 and is journaled for rotation 50 as at 27 and 28. One end 30 of shaft 25 extends through the journal 28 and outwardly through wall 16. An operating lever 32 is keyed to the end 30 of shaft 25 and is designed to rotate shaft 25 to operate the device in a manner to be de- 55

scribed. Spring 34, secured to lever 32 and wall 16, serves to restore the lever to normal position after the latter has been depressed and released.

Journalled for rotation in the side walls 12 and 16 above shaft 25 is a second shaft 36. A crank arm 38 is keyed at one end to shaft 25 and a crank arm 39 is similarly keyed to shaft 36. A link 40 is pivotally secured substantially at its extremities to the other ends of the crank arms 38 and 39. It is now apparent that upon downward movement of lever 32, shafts 25 and 36 are caused to rotate simultaneously in a counter-clockwise direction. The rotation of these shafts serves to exert a lateral component of force on the main operating bar 42, through the medium of the crank arms 44 and 45, and causes bar 42 to move towards the front of the apparatus in a vertical plane. As shown, one extremity of each crank arm 44 and 45 is keyed to shafts 25 and 36, respectively, and the other extremity of each crank arm is pivotally secured to main bar 42 as at 46 and 47.

A plurality of pusher arms 49 are pivotally secured to main bar 42 as at 50 and serve to eject the top sheets of paper from the stacks on being pushed forward by the main bar. These pusher arms extend through slot 20 in back stop 18 and normally rest on the top of the stacks 15; there being one such arm for each stack. Arms 49 are designed to have a free vertical movement about their pivots. The free end of each arm 49 is up-curved as at 52. The underside of each upturned end is knurled or serrated as at 53 so as to grip or catch the paper on forward movement of the arm and thereby eject the top sheet and to slide over the sheet on backward movement of the arm.

In operating my apparatus to collate sheets from a plurality of stacks of sheets, the stacks are placed on the platforms, one stack on each platform, and squared against side wall 12 and back stop 18 to crack the sheets. Arms 49 are placed on the tops of the stacks and lever 32 is depressed to cause the arms to push the individual top sheets 55 forwardly from the stacks to the position shown in Fig. 2. In this position, the sheets may be removed readily by the operator. On release of lever 32, arms 49 slide back over ejected sheets 55 and return to the initial starting position shown in Fig. 1 ready to eject the succeeding top sheets. It is, of course, apparent that arms 49 drop down, by their own weight, as the thickness of the stacks diminish by virtue of the ejection of successive top sheets and hence the arms always return in proper operative relation with respect to the top sheets in the stacks until all of the sheets have been ejected.

In order to avoid the possibility of an ejected sheet or sheets being pulled back by arms 49 on rearward movement thereof I provide retaining fingers 57, one for each stack, which hold the ejected sheets in place until they may be removed by the operator on release of lever 32. Retaining fingers 57 extend forwardly through slot 20 from a stationary standard 59 positioned in the housed portion of the apparatus. One end of each finger is pivotally secured to standard 59 as at 60 in substantially the same manner as arms 49 are secured to bar 42. The free end of each finger is pointed as at 62 and rests on the top of the stack. Fingers 57 follow the stacks of diminishing thicknesses down in the same manner as described above in connection with arms 49.

While I have described my device as being operated by a hand lever, it is, of course, manifest

that my device may be operated by a foot pedal through suitable linkage, or it may be driven electrically, as desired. Back stop 18 may be positioned normal to the base or it may be entirely omitted without affecting the operation of my device. Also, if desired, shelves 22 may be positioned horizontally. This latter positioning of the shelves is particularly desirable where the back stop is dispensed with.

I claim:

1. In a collating machine, means for supporting a plurality of individual stacks of paper sheets one above the other, a pusher arm resting on the top of each stack, means to urge said arms forwardly and thereby eject the individual sheets from the tops of the individual stacks and feed them forwardly to the desired collating position and means for preventing said ejected sheets from being carried backward onto the stacks.

2. In a collating machine, means for supporting a plurality of individual stacks of paper sheets one above the other, a pusher arm resting on the top of each stack, means to urge said arms forwardly and thereby eject the individual sheets from the tops of the individual stacks and feed them forwardly to the desired collating position and means for preventing said ejected sheets from being carried backwards onto said stacks, said means comprising a plurality of restraining fingers pivotally secured at one end to a stationary support, each of said fingers having a free end adapted to engage the top sheet of an individual stack.

3. In a collating machine, means for supporting a plurality of individual stacks of paper sheets one above the other, an operating bar, a plurality of pusher arms pivotally secured at one end to said bar, each of said arms having a free end adapted to rest on the top of an individual stack, means to urge said arms forwardly and thereby eject the individual sheets from the tops of the individual stacks and feed them forwardly to the desired collating position and means for preventing said ejected sheets from being carried backwards onto said stacks, said means comprising a plurality of individual restraining fingers pivotally secured at one end to a stationary support, each of said fingers having a free end adapted to engage the top sheet of an individual stack, said arms and said fingers being adapted to have an unrestrained movement in a vertical plane about their pivots.

4. In a collating machine, means for supporting a plurality of individual stacks of paper sheets one above the other, an operating bar, a plurality of pusher arms pivotally secured at one end to said bar, each of said arms having a free end adapted to rest on the top of an individual stack and means to urge said arms forwardly and thereby eject the individual sheets from the tops of the individual stacks and feed them forwardly to the desired collating position, said means including a pair of rotatable shafts, one above the other, and a pair of crank arms, each crank arm being fixedly secured at one end to a single shaft and the other ends of said arms being pivotally secured to said bar.

5. In a collating machine, means for supporting a plurality of individual stacks of paper sheets, a plurality of pusher arms ganged together, each of said arms having a free end adapted to rest continuously on the top of an individual stack, means to urge said arms forwardly and thereby eject the individual sheets from the tops of the individual stacks and feed

them to the desired collating position and means for preventing said ejected sheets from being carried backward onto the stacks.

6. In a collating machine, means for supporting a plurality of individual stacks of paper sheets one above the other, a plurality of pusher arms ganged together, each of said arms having a free end adapted to rest continuously on the top of an individual stack, means to urge said arms forwardly and thereby eject the individual sheets from the tops of the individual stacks and feed them to the desired collating position and means for preventing said ejected sheets from being carried backward onto the stacks.

13. 7. In a collating machine, means for supporting a plurality of individual stacks of paper sheets

one above the other, a plurality of pusher arms ganged together, each of said arms having a free end adapted to rest continuously on the top of an individual stack, means to urge said arms forwardly and thereby eject the individual sheets from the tops of the individual stacks and feed them to the desired collating position and means for preventing said ejected sheets from being carried backward onto the stacks, said means comprising a plurality of restraining fingers pivotally secured at one end to a stationary support, the other end of each of said fingers being adapted to engage continuously the top sheet of an individual stack.
